DESIGN FOR A CIGARETTE TRAY OR SIMILAR ARTICLE

Paul E. Flato, New York, N. Y.

Application June 28, 1940, Serial No. 93,308

Term of patent 3½ years

To all whom it may concern:

Be it known that I, Paul E. Flato, a citizen of the United States of America, residing in New York city, in the Borough of Manhattan, county and State of New York, have invented a new, original, and ornamental Design for a Cigarette Tray or Similar Article, of which the following is a specification, reference being had to the accompanying drawing, forming part thereof, wherein,

I claim:

The ornamental design for a cigarette tray or similar article, substantially as shown and described.

PAUL E. FLATO.
